MULTIPLE PORT CHARGE FORMING AND
DISTRIBUTING MANIFOLD

Arlington Moore, New York, N. Y.

Application April 23, 1931, Serial No. 532,151

7 Claims. (Cl. 123—52)

My invention relates to means for distributing the charge materials to the cylinders of an internal combustion engine, particularly eight-cylinders-in-line engines, or engines of a greater number of cylinders, and the same has for its object to provide a simple, compact, and efficient construction which is capable of effecting substantially uniform distribution of the charge materials in a homogeneous condition to the cylinders.

Another object of the invention is to provide a construction of the character specified in which the multiple ports thereof receive the charge materials through a common conduit.

Another object of the invention is to provide a construction of the character specified in which the passage thereof is disposed to positively deflect the charge materials into the first or inner port without materially interfering with the passage of the charge to the remote port.

Another object of the invention is to provide a construction of the character specified in which the passage thereof is formed to distribute the charge materials to either port without undue deflection of the charge or other interference with the passage thereof.

Another object of the invention is to provide a construction of the character specified which delivers the charge materials substantially equally quantitatively and qualitatively to the several ports.

Another object of the invention is to provide a construction of the character specified in which the passage thereof is formed to compensate for the greater distance of travel of the charge in passing to the remote port.

Another object of the invention is to provide a construction of the character specified in which the multiple ported branches thereof are formed separate or detachable from the entrance or central portion thereof.

Another object of the invention is to provide a construction of the character specified in which the passage thereof is formed to distribute or direct the charge to either port while allowing drainage of fuel and maintaining adequate velocity of the charge in its travel to the remote port.

Another object of the invention is to provide a construction of the character specified in which the passage formation is supplemented in causing equal or uniform distribution of the charge materials to the cylinders by the application of extraneous heat to the fuel component so as to effect substantially complete vaporization thereof and

maintain the charge in a homogeneous condition during the travel thereof through the branch passages to the ports thereof.

Another object of the invention is to provide a construction of the character specified in which the passages thereof are formed to effect equal distribution of the charge to the ports while maintaining the same in a homogeneous condition and causing the same to become or remain cool so as not to reduce the volumetric efficiency.

Other objects will in part be obvious and in part be pointed out hereinafter.

In the accompanying drawings:

Fig. 1 is a plan of one form of manifold constructed according to and embodying my said invention;

Fig. 2 is a sectional elevation thereof on the line 2—2 of Fig. 1;

Fig. 3 is an enlarged end view thereof with the branch of the intake conduit removed;

Fig. 4 is an enlarged section on the line 4—4 of Fig. 2;

Fig. 5 is an inverted plan of Fig. 4; and

Fig. 6 is a diagram illustrating the construction of the intake conduit.

The manifold embodying my said invention, as shown, is particularly adapted for an eight cylinder engine having four intake ports in the cylinder block, each to two cylinders, and six exhaust ports. The intake and exhaust ports are arranged in the same straight line. Four port manifolds, prior to the present invention, have not been favored for use in practice because of distributional defects therein, the dual manifold either with or without dual carburetion being largely used. With dual carburetion it is difficult to get the two carburetors to supply fuel at the same rate, causing roughness of engine performance, while with single carburetion the dual manifold comprises two sets of branches of unequal length having communication with the riser in offset relation to each other, which is liable to disturb the distribution because of turbulence or other causes. My invention enables the use of a four port manifold for uniform distribution of the charge to the cylinders without reliance upon the above expedients now resorted to in practice.

The manifold embodying my said invention includes as features thereof the inventions shown, described and claimed in my copending applications Serial No. 513,804, filed Feb. 6 1931, and Serial No. 514,105, filed Feb. 7, 1931. The constructions disclosed in said applications, as in this, are adapted to vaporize the fuel component

- enroute to the engine cylinders, to maintain adequate charge velocity for the stable entrainment of the fuel component without sacrifice of volumetric efficiency, to provide adequate facilities 5 for drainage of the branches during initial operation and for vaporization of the fuel thus drained, to concentrate substantially the hottest portion 10 of the intake conduit contiguous to the point of subdivision or deflection of the charge stream into the branches for causing the vaporization of fuel particles discharged through or thrown out of the charge stream at said point enroute to the engine cylinders, and to render the thermal efficiency of said central heated portion substantially maximum to cause fuel vaporization at a 15 rate to prevent accumulation of fuel in said heated portion and thermal decomposition of fuel to form tarry products liable to impair the thermal efficiency of the heated portion.
- 20 The fuel vaporizing and charge distributing manifold embodying my said invention is also adapted for use with carburetors or fuel supplying devices of various types such as with the apparatus disclosed in my copending application 25 Serial No. 525,992, filed March 28, 1931 and while the construction is particularly adapted for distributing charge mixtures containing fuel of high volatility, such as gasoline, charge mixtures containing less volatile fuels may be as effectively 30 distributed thereby in homogeneous admixture with the air.

In ordinary constructions the incoming charge picks up condensed fuel from the intake manifold walls. The condensation or loading up of 35 fuel in the intake manifold usually takes place during periods of low speed operation. The accumulated or condensed fuel swept into the engine cylinders, especially when the throttle is opened wide, causes waste of fuel, oil dilution, 40 non-uniform distribution with temporary over-richness of the mixture in certain of the cylinders, and other detrimental effects, resulting especially in roughness of engine operation. While various expedients have been resorted to 45 in order to obviate these defects, none of them has proved very successful.

In my invention I rely upon the suitable application of heat to the intake conduit whereby 50 the fuel component of the charge is completely vaporized and maintained homogenized enroute to the intake ports, and the maintenance of this condition is preferably supplemented or helped by providing branches of progressively decreasing cross-section such as disclosed as a feature of 55 the intake manifolds of said applications Nos. 513,804 and 514,105 and of my application Ser. No. 234,417, filed November 19, 1927, thereby promoting uniform distribution to the intake ports with resulting smooth, powerful and economical 60 engine operation.

65 Referring to the drawings, the intake manifold 10 (the form illustrated being of the down-draft type) is preferably located above the exhaust manifold 12, being associated therewith for heating purposes. The charge mixture passes into the manifold through the central neck portion or descender 14 formed integrally with the exhaust manifold and into the branches 16 and 18 and out through the ports 20 and 22 and 20^a 70 and 22^a. The branches 16 and 18 are preferably separately formed and are detachably connected to the central portion 14 as hereinafter more fully described.

75 With the form shown, neck 14 leads downwardly to communicate with the branches at substan-

tially the middle of the manifold and immediately above the entrances to its branches, and at this point a distributing chamber 24 is provided from which the mixture is supplied to the manifold branches through openings 26 and 28.

80 Entrances 26 and 28 are of enlarged cross-sectional areas as compared to the cross-sectional area of the openings 20, 22, 20^a and 22^a, and of reduced cross-sectional areas as compared to the cross-sectional area of the neck 14, and the cross-sectional area of the branches gradually decreases towards the ports 20 and 20^a to cause an increase in or maintain the velocity of the charge as the same travels to the ports.

85 The branches 16 and 18 each includes an inner elbow portion 30 for imparting a substantially right angular deflection to the charge through ports 22—22^a. The outer bend of the elbow portion, as indicated at 32, has a curvature such that the charge, following the same, is positively deflected or directed into the port 22—22^a. The straight outer portion 34 of the manifold has a communicating junction with elbow portion 30 at the outer bend 32 thereof as indicated at 36, said junction comprising a portion 38 merging 100 with the straight portion 34 and the curving portion 30, which portion 38 has a reverse curve relative to curve 32. The outer or remote port 20, 20^a communicates with portion 34 through the curving elbow portion 40 having a curvature 105 at 42 of longer radius than the radius of the curve 32 to insure easier deflection of the charge through port 20, 20^a.

90 When an intake valve in communication with the port 22, 22^a is opened, the intake valve communication with port 20, 20^a then being closed, the charge is guided and deflected by the elbow portion 30 through said port 22, 22^a, the curvature allowing an easy sweep of the charge through the port. The opening formed in the outer bend of 110 the elbow 30 by the junction at 36 reduces the wall area of the elbow and hence the drag or friction on the charge as it sweeps through port 22, 22^a. When an end cylinder is being filled, the charge entering the branch through entrances 26 115 or 28 is deflected by the reverse curved portion 32—38 into the portion 34 located in off-set relation to the axis of the entrance 26 or 28 but parallel therewith. The deflection however is substantially less than the deflection of the charge 120 through port 22, 22^a, the curvatures also being such as to insure an easy sweep of the charge 125 through the portion 34.

95 The branches 16 and 18 each preferably comprises an upper part 4 of substantially uniform 130 cross-section, preferably semi circular, from the inner end thereof to the elbow 40 thereof, and preferably horizontal, and a lower part 46 at the base thereof merging into the upper part 44 and likewise extending from the inner end of the 135 branch into the elbow 40 thereof and gradually decreasing in cross-sectional area or depth towards each elbow, the upper part 44 forming the major part of the branch and the lower part 46 the lesser part. The lower portions 46 jointly 140 with the upper portions 44 form passages providing the relatively large entrances 26 and 28 and gradually decreasing in cross-sectional area to said elbows 40.

145 The desired inclination of the floor of the intake conduit branch and the tapering thereof as a whole is obtained as illustrated in Fig. 6, representing successive cross-sections taken on the lines x, y, and z of Fig. 1. The cross-section at the elbow 40 is a circle x having a radius r. The 150

cross sections of the upper portion 44 from the elbow inwardly are partial circles x' , x'' having the same radius r , the centers c of the several circles lying on the same horizontal line. The cross sections x' , x'' however are enlarged progressively towards the inner end of the branch, the lower portion 46 having cross-sections conforming to partial circles a , b , having the same radii r and described about centers c' , c'' located vertically below the centers c and progressively increasing in distance therefrom, the partial circles a , b , merging with the partial circles x' , x'' .

By progressively enlarging the general contour of the branch at the bottom, the branch is made to incline downwardly towards the center of the manifold at a substantial angle for drainage purposes, as indicated at d , Fig. 6. At the same time the branch passage varies in cross section as a whole at a rate determined solely by the variations in cross section of the relatively smaller lower portion 46, the rate of variation in cross section of the branch passage as a whole being less than the rate of variation in cross-section of the lower portion 46. The lower portions 46 therefore provide sufficient inclinations for drainage and effect relatively slight progressive restriction of the branches to cause acceleration ratio proportional to distance traveled by the charge materials to effect uniform delivery through all ports.

The branches 16 and 18 are cast as separate open ended units or members with flange portions 48 contiguous to their inner ends adapted to register or fit corresponding bosses or portions 50 formed on the central portion 14 and disposed about the entrances or openings 26 and 28 therein. The branches are secured in position by means of the bolts 52 extending through the flanges 48 into the bosses 50, gaskets 54 being interposed between the flanges and the bosses for producing a tight joint. The gaskets 54 are preferably composed of a material thermally insulating the branches from the central portion 14.

The exhaust manifold 12 is preferably of the type in which the exhaust gases are conducted from the cylinders towards the middle and out through a central outlet 56, the branches 58 and 60 thereof having openings 62 adapted to register with the exhaust passages of the cylinder block.

In the present embodiment of the invention the exhaust gas manifold branches are disposed in spaced relation to the intake branches, providing cooling air gaps 64 therebetween, which, as shown at Fig. 2, increases in width towards the outer ends of the manifold.

The intake conduit 10 at the junction of the branches thereof opposite the neck 14 is provided with a wall portion 66 extending downwardly into the exhaust passage coaxially with and in spaced relation to the walls of the outlet 56, i. e., substantially at the point where the two exhaust gas streams unite, which is substantially the hottest part of the exhaust gas. The upper end of the portion 66 opens into the intake manifold and the lower end thereof is closed by a dome shaped member or wall portion 68 in spaced relation thereto to form a substantially annular chamber 70 opposite the inlet 14 at the point of subdivision of the charge mixture stream but lying substantially beyond the path of travel thereof, the upper end of the dome preferably lying entirely below the plane of the intake branches.

The portion 68 is preferably separate from the portion 66, the former preferably being composed of a material of high heat conductivity, such as copper. The interior 72 of the portion or member 68 is exposed to the hot exhaust gases, the member preferably having means formed to insure positive circulation of the hot exhaust gases therethrough.

This means in the present embodiment of the invention includes a deflector or baffle 74 forming an integral extension of the relatively massive lower portion 76 which forms a heat reservoir integral with the dome 68 and lies within the exhaust gas outlet 56. The baffle 74 extends into the chamber 72, substantially bisecting the same and terminating short of the top thereof. This forms a return bend passage having an entrance 78 through which a portion of the hot exhaust gases are bypassed from the outlet portion 56 and directed into contact with upper portion of the dome. The bypassed exhaust gases pass out directly to atmosphere through an outlet opening 80 at the opposite end of the return bend passage 72, thereby accelerating the circulation and keeping the dome heated to a maximum. The dome 68 may be knurled or roughened to transfer heat to the fuel at maximum rate and reduce film deposit. The member 68-76 is preferably threaded into the portion 66, as indicated at 82.

The exhaust manifold 12 is arranged to supply heat to the neck 14 of the intake manifold by surrounding the neck with a jacket extension 84 of the exhaust manifold, which jacket is vented directly to atmosphere through outlet opening 86 at the upper end thereof to insure positive circulation of hot exhaust gases through the jacket 84.

The exhaust gases discharged through the outlet openings 80, and 86 are carried to a remote point through a common conduit 88. The conduit 88 at its upper end has a flange 90 adapted to engage the portion 92 about the outlet 86 and to be secured thereto by screws 94. The conduit 88 extends downwardly substantially parallel with the descender 14 and with the main exhaust discharge outlet 56. The exhaust gases discharged through outlet opening 80 are conducted through a transverse conduit or pipe 96 communicating with and connected to the pipe 88 at 98. The pipe 96 has a telescoping end portion 100 extending into the outlet opening 70, and a flange 102 for securing the same to the portion 56 by screws 104.

The neck 14 is terminated in a sharp angle, as indicated at 106, to shed off any liquid fuel from the neck wall into the air stream.

The annular well 70 between the walls 66 and 68 is subject on both sides to the most concentrated heat from the exhaust gases. The massive metal member 76 of copper, catalytic alloys, or the like, serves as a thermal reservoir for uniform supply of heat to the dome 68 by conduction.

An air bleed through passage 108 serves to supply air for scavenging fuel in crucible 70 to facilitate the returning of the vapors into the intake during engine operation, or if liquid fuel should accumulate in the well 70 it can run out through said passage 108.

The fuel, when gaseous injection is employed for blasting the same into and through the air stream in neck 14, is very thoroughly pulverized by reason of its greater velocity, and by reason of its resulting great surface exposure to the air

- absorbs heat therefrom very rapidly. Rapidity of heat absorption is of utmost importance because of the extremely short interval of time available and which is longest with the slow 5 charge travel during engine idling and shortest with the high speed charge travel encountered at full power operation. Heavy fuel, when used, is capable of taking up more heat than on operation with lighter and more volatile fuels. The 10 heat of the charge is thus reduced so as to favor having high density charge productive of good volumetric efficiency, and the fuel is in large part put into such condition—gasified and/or vaporized and/or in fogged or like highly divided state, 15 that it is suspended in and carried along with the air stream without condensation or deposition on the conduit walls as the air stream branches or changes direction on its way to the engine cylinders.
- 20 The stream of blasted fuel, or fuel carried by the air from an ordinary carburetor, usually contains some fuel portions or droplets heavy enough to continue their substantially straight line travel without material deflection with the moving air.
- 25 Unless given a liberal application of heat, this fuel portion would wet and load up the walls of the intake manifold.

30 By changing the direction of the intake manifold passage in the neighborhood where the blasted or inertia impelled heavier fuel particles strike the conduit walls, I can carry the lighter fuel particles thoroughly suspended in the air stream towards the engine cylinders with the air stream, and by applying heat of the exhaust 35 gases to the intake conduit walls, I am enabled to secure a selective application of heat to vaporize and suspend this fuel without undesirably heating the air of the charge.

35 The illustrated mode of securing such effect is 40 by directing the fuel blast or fuel charge mixture downwardly in the intake manifold neck 14, which at the bottom branches to each side, while applying heat of exhaust gas without such neck by surrounding it with the exhaust gas chamber 45 84, thus providing a hot surrounding wall adapted to be contracted by and apply heat to the heavy particles of fuel spreading to the outer region of the blast fuel stream, and by providing the hot cup or crucible 70 in line with the discharge end of the neck 14, where the convex 50 heated portion 68 also radiates heat to the charge passing to the cylinders or is struck by and supplies vaporizing heat to the heavy fuel particles projected thereon to complete the vaporization.

55 Inasmuch as the exhaust gas from all the exhaust ports is directed into the vicinity of the crucible 70, the crucible is subjected to the maximum temperature available. The annular crucible is in contact at both sides with the exhaust gas, and provides a doubly extended surface, compared to the surface of an ordinary non-annular cup, for heating the projected fuel, the heating effect being augmented by the positive deflection 60 of a portion of the exhaust gases into the interior of the dome 68. By disposing the convex dome 65 68 in the path of downwardly projected fuel, the impact of the fuel particles thereon cause the particles to be reflected therefrom or to be deflected without tending to conglomerate or accumulate thereon, as such particles would be likely to do if the surface were flat, an extended 70 downwardly curving surface being provided along which the fuel particles may gravitate until vaporized, thereby enhancing vaporization or fuel

nebulizing without the accumulation of liquid fuel in the bottom of the crucible 70. The vaporizing effect is also assisted by the provision of a down-draft manifold in which the fuel particles are caused to positively gravitate in the direction of air flow into the crucible and onto the dome, the incoming particles being subjected to air passing through the opening 108 and moving in the opposite direction. 80

The temperature available with my manifold, particularly at the higher speeds, are sufficient to cause the fuel particles to assume the spheroidal state, evidenced by the fact that the fuel does not form tarry or other solid precipitates within the crucible 50 and the vapor produced is substantially dry and less liable to condense. 85

Extraneous heat for vaporizing and homogenizing the fuel component is thus applied in an efficient manner prior to the deflection of the charge into the branches, and during the downward travel thereof. The cross-sectional area of the neck 14 is preferably greater than the mean cross-sectional area of the branch to retard the velocity of the charge during the vaporizing stage, and the length of the neck 14 90 is such that substantially complete vaporization of the fuel component is effected by the several heating means 68 and 84 during the time interval of vertical travel of the charge, thereby forming a stable homogeneous mixture, the stability of 95 which is enhanced because of the spheroidizing effect of the crucible 70. By applying preliminary heating or part of the heating to the neck 14 through jacket 84, localized wetting down of the vertical passage due to cold walls is also 100 prevented, and washing down of deposited fuel into the branches to cause non-uniform distribution to the cylinders or other detrimental effects cannot occur. 105

110 The heating capacity of the dome 68 depends on the area of the surface thereof and on the flow of exhaust gas through the interior thereof. The diameter of the dome 68 is preferably made greater than the diameter of the passage through the neck 14 in alignment with said dome so that 115 projected fuel particles passing from the neck 14 are sure to contact with said dome to complete the vaporization. 120

125 The application of extraneous heat substantially in the locality where the fuel is introduced into the air in a highly comminuted or atomized state, and before such fuel condenses on the wall, facilitates vaporization, and the application of heat for vaporizing is accomplished here without appreciably expanding the charge, because the heat absorption by the fuel is then high relative to the heating. The dome 68 has a high heat radiating capacity because of its thinness and composition but the heating action thereof does not appreciably affect the charge density 130 because the dome lies substantially out of the path of travel of the charge and the heat absorption is high. 135

140 By the combined effect of the contact of the fuel particles upon these wall surfaces, and the efficient application of heat thereto, the homogeneous suspension of the fuel in the air is completed, without undue air heating and loss of volumetric efficiency through air heating and charge density reduction. 145

To maintain the homogeneous suspension of the fuel in the air so attained, I now keep the sectional area of the intake manifold branches, and, therefore, of the moving charge stream as low as practicable without unduly restricting 150

- charge flow, thus keeping the charge moving rapidly and avoiding any slowing up or expansion of the charge material on its way to the engine cylinders, which would be productive of condensation, and I also preferably progressively increase the charge velocity during such travel, as by progressive reduction of the cross-sectional area of the manifold branches from the common neck portion thereof to the engine cylinders.
- 10 The intake branches 16 and 18, being separated from the exhaust manifold 12 by gaps 64, are substantially entirely insulated from the exhaust manifold by the surrounding air, or other cooling medium, so that no heating is applied to the charge in the branches after deflection of the charge thereinto, whereby a cool dense charge is caused to enter the cylinders in a homogeneous condition. The intake branches 16 and 18 because of their detachability can be and are preferably composed of a material of relatively high thermal conductivity, such as cast aluminum, capable of rapidly conducting away surplus heat to cause the charge to become cool and dense, or to maintain such charge in that condition. By the use of a material, such as cast aluminum, the interior walls of the manifold branches can be made much smoother than where cast iron is used, reducing skin friction tending to retard the charge velocity so that fuel precipitation is less liable to occur.
- 15 The result is that a cool dense charge is delivered to the ports 20 and 22 and 20^a and 22^a of the lateral branches 16 and 18, the charge being uniformly distributed in a homogeneous condition to the cylinders in substantially the proportions for which the carburetor or other fuel supplying device is economically set.
- 20 The floors 46 taper from least at the outer ends of the intake manifold branches to largest depth where they lead down into the annular well 70. The decrease in section of the intake manifold speeds up the charge as it travels to the engine cylinders thereby opposing any tendency of fuel particles to deposit on the walls.
- 25 By venting the annular well 70 to the atmosphere at its bottom through passage 108 any liquid fuel which may run back from the branches and accumulate in well 70, as for example, at starting, or upon pumping in extra fuel for acceleration, will not simply boil or distill off, but can either run out through such vent, or, in case the intake depression is relatively high, be carried along upwardly as vapor with air admitted through the opening 108.
- 30 That the hot wall surfaces are of sufficient area and mass to supply vaporizing heat to the relatively large quantity of liquid fuel blasted or otherwise projected thereagainst during full power operation insures plenty of heat being available when the same walls are used for communicating heat to the fuel when supplied in smaller quantities, even though the temperature of such walls is then lower. Owing to the heat available through the walls of the crucible 70, vaporization of fuel is accomplished without the formation of tarry products liable to reduce the thermal efficiency thereof because of the insulating effects of such tarry formations.
- 35 The charge so produced in passing to the cylinders through the branches 16 and 18 remains in a homogenized state, without substantial precipitation of fuel, due to the efficient vaporizing and spheroidizing action imparted thereto prior to the entrance of the charge into the branches, thereby rendering unnecessary the application of additional heat to the same in the branches, so that the charge, being unheated, passes to the cylinders in a relative dense state productive of maximum power.
- 40 The thermal vaporizing effect of the manifold may be augmented by discharge of the fuel into the region of intake depression at the engine side of the throttle as set forth in my said application Serial No. 525,992, the manifold being equally efficient, however, with conventional carburetors, such as those connected below the throttle. The manifold can be adapted to meet any engine or fuel requirement by slight variation in the thermal and other relationships of the parts.
- 45 By my invention, the application of heating to the charge is restricted to the central portion of the manifold, as the charge travels downwardly at a somewhat retarded velocity. No heat is applied to the branches which are constructed to maintain the charge cool and also to maintain sufficiently high velocity thereof to retain the fuel in suspension. The neck or central portion 14 of the intake manifold and the exhaust manifold 12 are formed integrally preferably of cast iron. The use of cast aluminum is preferable for the branches because of its relatively greater thermal conductivity and capability of being made smooth. The branches are therefore made detachable or separate from the cast iron portion to enable the utilization of such heterogeneous metals. Making the branches separate facilitates molding or casting of the parts and allows access to the interior thereof for machining the inner surface. Separate or detachable branches may be supplied in various shapes or sizes to enable fitting thereof to various types of engines and to engines of different characteristics, and this method of construction enables the particular branch to be adopted which suits the individual needs. The jointed connection at the inner end of the branch also provides compensation for strains and stresses due to the heating and cooling of the manifold, this type of construction being less liable to crack than an integral construction. The aluminum branches 16 and 18 are separated from the exhaust conduit by the air gaps 64 and are insulated from the heated portion by the gaskets 54. The result is that the charge in the branches becomes or remains cool and dense, obviating the danger of overheating the charge so as to impair the volumetric efficiency.
- 50 Having thus described my invention what I claim and desire to secure by Letters Patent is:
1. An intake manifold comprising a multiple ported conduit, a portion of said conduit including means for deflecting the charge into the inner port, and said conduit decreasing in cross-sectional area towards the outer port.
  2. An intake manifold comprising a multiple ported conduit including an elbow entrance portion for deflecting the charge to the contiguous port, and forming a portion of the passage to the remote port, said conduit decreasing in cross-sectional area towards the remote port.
  3. An intake manifold comprising a branch having multiple ports, and including an elbow entrance portion for deflecting the charge to the inner port and an offset outer portion leading to the more remote port and having a communicating junction with the outer bend of said elbow portion, said conduit decreasing in cross-sectional area along said elbow portion and outer portion towards the remote port.
  4. An intake manifold comprising a branch

having an entrance thereto at one end and a plurality of ports beyond said entrance at the same side of said branch, the upper part of said branch forming a substantially horizontal partial passage of substantially uniform cross-sectional area and the lower part of said branch being inclined downwardly relative to the upper part from adjacent the outer port to the entrance and forming a partial passage of decreasing cross-sectional area in the direction of the outer end thereof, whereby to decrease the branch passage in cross-sectional area as a whole at a relatively lesser rate than the rate of decrease of the lower passage portion, the cross-sectional area of the branch at 15 the inner port being greater than that of said inner port.

5. An intake manifold comprising a multiple ported branch including an elbow entrance portion for deflecting the charge to the inner port 20 and an outer portion having a communicating junction with said elbow portion at the outer bend thereof, the base of said branch being inclined downwardly substantially from the outer port to the entrance to the elbow portion.

25 6. An intake manifold comprising a branch having a plurality of ports disposed longitudinally

thereof in substantially a horizontal plane, said branch including an elbow entrance portion for directing the charge to the inner port and an outer portion extending to the remote port and having a communicating junction with the elbow portion at the outer bend thereof in offset relation to the entrance to the elbow portion, the upper part of said branch including said portions being of substantially uniform cross-sectional area, and the lower part thereof being of progressively increasing depth towards the inner end thereof for draining the branch and producing a branch passage decreasing in cross-sectional area as a whole towards the outer port.

7. An intake manifold comprising a multiple ported branch including an elbow entrance portion for deflecting the charge towards the inner port, a portion having a communicating junction with the elbow portion at the outer bend thereof, and an elbow portion at the outer end of the second named portion leading to the outer port, said second named portion decreasing in cross-sectional area to said outer elbow portion, and said outer elbow portion having a greater radius of curvature than the inner elbow portion.
